UNITED STATES PATENT OFFICE

161,073

GUN SIGHT

Harvey A. Williams, Davison, Mich.

Application April 8, 1949, Serial No. 1,867

Term of patent 14 years

(Cl. D30—1)

To all whom it may concern:

Be it known that I, Harvey A. Williams, a citizen of the United States, residing at Davison, in the county of Genesee and State of Michigan, have invented a new, original, and ornamental Design for Gun Sight, of which the following is a specification, reference being had to the accompanying drawing, forming a part thereof, in which:

Fig. 1 is a side elevational view of a gun sight showing my new design;

Fig. 2 is a front elevation thereof;

Fig. 3 is a side elevation taken oppositely to Fig. 1;

Fig. 4 is a plan view thereof; and

Fig. 5 is a perspective view thereof.

I claim:

The ornamental design for a gun sight, as shown.

HARVEY A. WILLIAMS.
